CLAIM

The ornamental design for a maternity brassiere closure, as shown and described.

DESCRIPTION

FIG. 1 is a front elevational view of a maternity brassiere closure showing our new design;

FIG. 2 is a rear elevational view thereof;

FIG. 3 is a bottom, left side, front perspective view thereof;
FIG. 4 is a left side elevational view thereof, the right elevational view being mirror-symmetrical thereto;

FIG. 5 is a front elevational view of the separated closure;
and,

FIG. 6 is a rear elevational view of the separated closure.
